SMOKING PIPE REAMER
Anthony Cuchiara, 113 Columbia St.,
Schuylkill Haven, Pa.
Filed Sept. 24, 1959, Ser. No. 842,093
2 Claims. (Cl. 131—246)

This invention relates generally to smoking accessories, and is particularly concerned with a novel construction of reamer or scraper for the bowl of a smoking pipe. The device of this invention is an improvement over the device of my prior U.S. Patent No. 2,891,559.

It is one object of the present invention to provide a pipe reamer which is more easily assembled in manufacture, and capable of quick and easy disassembly, as for cleaning, repair and replacement of parts, all without the exercise of more than average skill or the use of special tools.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a side elevational view showing a pipe reamer of the present invention in operative association with a pipe, the latter being shown partially and in phantom for clarity of understanding;

FIGURE 2 is a transverse sectional view through the instant reamer, taken along the line 2—2 of FIGURE 3;

FIGURE 3 is a longitudinal sectional view through the reamer of the instant invention, taken substantially along the line 3—3 of FIGURE 2;

FIGURE 4 is an exploded perspective view illustrating the parts of the instant invention in a disassembled condition; and

FIGURE 5 is a partial, longitudinal sectional view similar to FIGURE 3, but illustrating an intermediate stage of assembly and disassembly of the instant pipe reamer.

Referring now more particularly to the drawings, and specifically to FIG. 1 thereof, a smoking pipe is there generally designated 10, which is conventional and includes a bowl 11 and stem 12. Received in the bowl 11 for scraping engagement with the interior thereof is a pipe reamer or scraper of the present invention, generally designated 15.

As best seen in FIGURES 2, 3 and 4, the pipe reamer includes an elongate hollow carrier, body or tube 17, which may be of generally cylindrical external configuration, and interiorly hollow. More specifically, the carrier or tube 17 may have a generally rectangular internal cross-sectional configuration, so as to define one pair of facing, spaced internal walls 18, and an additional pair of facing, spaced internal walls 19 disposed at right angles to the walls 18. The walls 18 and 19 are all longitudinally coextensive with the tube 17, the walls 18 being wider than the walls 19, with each facing pair of walls being in substantial parallelism with each other.

Adjacent to but spaced upward from the lower carrier end 20, there are formed in the carrier a pair of diametrically opposed through openings or slots 21 extending longitudinally of the carrier and longitudinally coextensive with each other. The slots 21 are arranged to open into the interior of the carrier 17 through respective internal walls 19, and are each of a width substantially equal to that of the respective internal wall 19. Thus, the longitudinal side edges of the slots 21 are sub-

2

stantially flush with the internal walls 18. Each slot 21 has an enlarged central portion 22 of arcuate or part circular formation. The central portions 22 are located on opposite sides of the carrier 17 and are joined by a groove 23 in each of the walls 18. The portions 22 and the grooves 23 form a substantially circular passage through the carrier to receive a coil spring 40 in the manner indicated in FIGS. 4 and 5.

The carrier slots or openings 21 are considerably spaced from the upper carrier end; and, located between the upper carrier end and the slots is a cross piece or handle rod 24. The cross piece or rod 24 extends diametrically through and is fixedly secured in the carrier 17, projecting beyond opposite sides thereof, at a location adjacent to and spaced from the upper end of the carrier. The rod 24 may lie in a plane substantially coplanar with that of the slots 21 to minimize space requirements, as will appear presently.

In the assembled relation of FIGURES 2 and 3, a pair of substantially identical, generally flat plates or blades 26 extend through respective carrier slots 21, with the blades in substantially coplanar relation. The plates or blades 26 are of a thickness relative to the width of the slots 21 and the distance between the facing internal walls 18 so as to be slideable therebetween, both vertically or longitudinally, and horizontally or laterally, and limited against movement out of their coplanar relation.

As best seen in FIGURE 3, each of the plates or blades 26 is generally H-shaped including a central, lateral portion 27 received in its respective slot and having a vertical or longitudinal extent, or length defined between upper and lower edges 28 and 29, respectively, appreciably less than the length of the receiving slot. It will be noted that the upper and lower edges 28 and 29 of the medial, central or lateral portion 27 of each H-shaped plate 26 extend generally normal to the axis of the carrier 17. In addition, each rigid H-shaped plate or blade 26 includes an external longitudinal portion 30 located outward of the lateral portion 27 exteriorly of the carrier body 17, and an inner or interior longitudinal portion 31 located radially inward of the lateral plate portion and interiorly of the carrier body. The exterior longitudinal plate portion 30 of each plate extends in opposite directions longitudinally of the carrier body 17, as at 33 and 34, beyond the upper and lower ends of the adjacent slots 21. Further, the longitudinal external end extensions or fingers 33 and 34 are preferably in substantial alignment to define a substantially straight, external longitudinal edge 35, which has its lower end rounded, as shown. The upper or distal end of the finger or upward external extension 33 terminates in spaced relation below the cross piece 24, while the lower or distal end of the depending finger or extension 34 terminates adjacent to and spaced just slightly above the lower body end 20.

It may also be seen in FIGURE 3 that the inner longitudinal portion 31 of each plate 26 includes a downwardly extending end or finger 36, extending appreciably beyond the adjacent, lower end of the respectively adjacent slot 21, and includes an upper end or finger 38 extending vertically upward slightly beyond the upper end of the adjacent slot.

The generally H-shaped plates or blades 26 may be received in the respective slots or openings 21 for vertical or longitudinal movement limited by engagement of the upper and lower lateral portion edges 28 and 29 with the upper and lower ends of the slots, and for limited lateral movement toward and away from each other in substantially coplanar relation with each other, by reason of the spacing between the interior longitudinal plate portion 31, and the spacing between the interior longitudinal plate portion 31 and the exterior longitudinal plate portion 30 of each plate. As shown in FIGURE

3; the plates 26 are in a normal, operative position within the slots 21, with the upper edges 28 of the lateral plate portions 27 proximate to the upper ends of the slots 21, and the lower edges 29 of the lateral plate portions spaced appreciably above the lower ends of the slots. The spacing between the lower lateral portion edges 29 and the lower ends of the slots 21 is sufficient such that upon downward longitudinal movement of the plates 26 to engage the edges 29 with the lower slot ends, the upper extensions or fingers 38 of the interior longitudinal plate portion 31 terminate vertically short of the upper ends of the slots. This position permits outward swinging movement of the fingers 38, as illustrated in FIGURE 5, exteriorly through the adjacent slots 21. Of course, from this condition, a plate 26 may be readily removed and separated from the carrier 17, by laterally outward and upward withdrawal of the interior portion finger 36 from its adjacent slot 21. In the normal or operative condition of FIGURE 3, and even in an extreme condition of longitudinal upward plate movement to engage the plate edges 28 with the upper ends of the slots, the depending fingers 36 extend beyond the lower ends of the slots to prevent withdrawal of the plates from the carrier.

Each plate 26 is provided with formations in the form of a pair of slots or notches 44 extending in vertically or longitudinally spaced relation through the inner edge of the inner longitudinal portion 31 and into the medial or lateral portion 27. The formations 44 of each plate 26 are located in alignment with each other, and in alignment with the openings 22 and grooves 23 of the carrier 17, when the plates are in their normal, operative position of FIGURE 3.

Suitable resilient means, such as a coil compression spring 40, is arranged interiorly of the hollow tubular body 17, extending along the passageway defined by the openings 22 in grooves 23, having its opposite ends connected to respective plates 26 and yieldably maintaining the latter in a position of movement away from each other. More specifically, the opposite end convolutions of coil spring 40 are respectively engaged in the pair of notches 44 of each plate 26, while the spring is conformably received in the passageway 22, 23, to yieldably and resiliently maintain the plates 26 in their normal position of longitudinal movement proximate to the upper ends of the slots 21, and in their laterally or radially outer position with the fingers 36 and 38 of the longitudinal interior plate portion in abutting engagement with the internal carrier wall 19.

To assemble the elements shown separated in FIGURE 4, it is necessary to first pass the spring 40 into the passageway 22, 23, and with one end convolution of the spring engaged in the slots 44 of a plate 26, to engage the lower, longer interior finger 36 of the plate inward and downward through the adjacent slot 21, and continue inward movement of the plate until the upper interior finger 38 is received in the slot. Resilient deflection of the spring 40 easily permits this manipulation, and reception of the spring in the passageway 22, 23 urges the plate longitudinally upward to its normal position of FIGURE 3 with the upper interior finger 38 extending beyond the upper end of the adjacent slot. The other plate 26 may be assembled in the same manner, and disassembly may be effected by mere reversal of the above described procedure.

From the foregoing, it is seen that the present invention provides a pipe reamer which fully accomplishes its intended objects, and is well adapted to meet practical conditions of manufacture and use. For example, as seen in FIGURE 1, the plates 26 are deflected laterally inward for conforming scraping engagement with the interior of the pipe bowl 11, and it is only necessary to manually rotate the carrier 17 to effect the desired reaming action.

Although the present invention has been described in some detail by way of illustration and example for purposes of clarity of understanding, and for compliance with section 112, Title 35 of the U.S. Code, it is understood that certain changes and modifications may be made within the spirit of the invention, and that the appended claims should be construed as broadly as the prior art will permit. For example, it is understood that the various components may be fabricated of any desired material, and by way of preference, without limiting intent, it is thought advantageous to form the carrier body 17 of aluminum, and the blades 26 of stainless steel.

What is claimed is:

1. A pipe reamer comprising a tube, said tube being formed adjacent to and spaced from one tube end with a pair of diametrically opposed longitudinally extending slots each having an enlarged medial portion in alignment with the other, a pair of generally H-shaped plates each having its lateral portion extending laterally through a respective slot and having its pair of longitudinal portions respectively interiorly and exteriorly of said tube, said lateral portion of each plate being of a dimension longitudinally of its receiving slot less than the receiving slot length and of a dimension laterally between said longitudinal portions greater than the tube wall thickness for longitudinal and lateral shifting of said plates with said lateral portions in said slots, the interior longitudinal portion of each plate having one relatively short end extending away from said one tube end and the combined longitudinal dimension of said lateral portion and the relatively short end of said interior longitudinal portion being less than the length of the receiving slot, the interior longitudinal portion of each plate having its other end relatively long extending toward said one tube end and the combined longitudinal dimension of said lateral portion and the relatively long end of said interior longitudinal portion being greater than the length of the receiving slot, said plates each being withdrawable from said tube upon longitudinal movement to its limiting position toward said one tube end and outward swinging movement of said relatively short end of said interior longitudinal portion, and a coil compression spring extending laterally through said tube and the enlarged medial portions of said slots to be held thereby against movement longitudinally of said tube, said plates each being configured with a laterally inwardly facing formation for conformably receiving a respective end of said spring when said plates are in their limiting position of longitudinal movement away from said one tube end, whereby said spring urges said plates laterally outward to a limiting lateral position with said interior longitudinal portion abutting the interior of said tube and retaining said plates in their limiting position of longitudinal movement away from said one tube end to prevent inadvertent removal of said plates from said tube.

2. A pipe reamer according to claim 1, said tube having a generally rectangular internal cross sectional configuration to define two pairs of facing internal walls, said slots being formed in said tube to open inwardly through one pair of facing internal walls, the other pair of facing internal walls defining guideways constraining said plates to movement in substantially coplanar relation with each other.
